UNITED STATES PATENT OFFICE.

CHAUNCEY R. PELTON AND HAROLD W. HOUGHTON, OF DETROIT, MICHIGAN, ASSIGNEES TO PELTON & CRANE COMPANY, OF DETROIT, MICHIGAN, A CORPORATION OF MICHIGAN.

DENTAL AND SURGICAL LAMP.

Application filed May 16, 1923. Serial No. 639,311.

To all whom it may concern:

Be it known that we, CHAUNCEY R. PELTON and HAROLD W. HOUGHTON, citizens of the United States, residing at Detroit, in the county of Wayne and State of Michigan, have invented certain new and useful Improvements in Dental and Surgical Lamps, of which the following is a specification.

This invention relates to dental or surgical lamps, and has for its object a lamp especially designed for use behind the teeth. Incandescent electric lights for this purpose are not broadly new, but so far as we know, no one has heretofore designed a lamp that has the advantages and obtains the results of our improved lamp.

It is the object of the invention to provide a lamp which is most convenient to handle and use and which at the same time can concentrate the rays on a definite spot without undue dispersion of light. This we accomplish by the design about to be described.

In the drawings:

Fig. 1 is an enlarged elevation of some of the lower front teeth showing the use of the lamp behind the teeth.

Fig. 2 is a longitudinal section of the lamp.

Fig. 3 is a section taken on the line 3—3 of Fig. 2.

Fig. 4 is a section taken on the line 4—4 of Fig. 2.

Fig. 5 is a fragmentary elevation of the head of the lamp.

A long slender glass tube *a* is employed with an opaque glass covering *b*, preferably a glossy white. This glass tube has a serpent's head or a bulbous portion provided with a single eye or lens *c* at the flat side of the serpent's head for the purpose of transmitting the light rays. The glass in this lens is thickened in a lens-like manner. The opaque coating *b* extends around the larger portion of the serpent's head but is omitted over the lens. The filament is located in the serpent's head or in close proximity thereto. By making the head in the form of a serpent's head, or bulbous, this enlarges this portion of the tube so that the opaque coating can be brought close to the side of the lens to prevent any side dispersion of the light rays. This is es-

pecially advantageous in illuminating teeth as illustrated in Fig. 1. The light will be concentrated in a relatively small ring. The letter *d* represents the outline of the lens, and letter *e* shows the light spot passing through the teeth and of a slightly greater diameter than the lens. This, in a measure, indicates how by enlarging the tube at the end to form a serpent's head, a fairly flat surface can be afforded for the desired dimensioned lens without in effect bending the lens to as to cause it to disperse the light at the sides.

The filament within the elongated tube may be supported in any suitable way. We have shown it supported in a separate sealed minute glass bulb on the end of a silk-wrapped cord, but obviously other ways could be adopted.

Not only does this form of lamp secure a better ray projection on the parts under examination, but it is much easier to handle than either a straight elongated tube or a crooked elongated tube with the lens in the end of the tube. In either one of these forms, the lens must be very much more sharply convex and consequently the ray dispersion is very much greater. In short, our form of lamp affords a very much better spot light than either of the forms referred to. It is a concentration of the light rays in a single spot that is desirable in work of this kind.

What we claim is:

1. A dental or surgical lamp, comprising an elongated transparent tube having at the end an enlarged bulbous head, thickened on one side thereof to form a lens, a non-transparent white glass covering entirely surrounding said transparent tube except at the lens portion thereof, and light projecting means within said bulbous head.

2. A dental or surgical lamp, comprising an elongated transparent tube having at the end an enlarged bulbous head and formed with a lens on one side of said head, a non-transparent glass covering surrounding said transparent tube and bulbous head with the exception of the lens portion, and light projecting means within said bulbous shaped head.

3. A dental or surgical lamp, comprising an elongated transparent tube having at the

end an enlarged bulbous head provided on one side of the head with a lens of relatively smaller diameter than the head, a non-transparent glass covering surrounding said transparent tube and head with the exception of the lens portion, and light projecting means within said bulbous shaped head.

4. A dental or surgical lamp, comprising an elongated transparent tube having at the 10 end an enlarged bulbous head provided on one side with a relatively flat portion pro-

vided with a transparent lens of smaller diameter than the head, a non-transparent glass covering surrounding said tube and enlarged head with the exception of the 15 lens portion, and light projecting means within said bulbous shaped head.

In testimony whereof we affix our signatures.

CHAUNCEY R. PELTON.
HAROLD W. HOUGHTON.
